J. P. BURGHER

CENTERING AND CEMENTING DEVICE

Filed June 19, 1922

Patented Sept. 4, 1923.

1,466,986

UNITED STATES PATENT OFFICE.

JOHN P. BURGHER, OF LONG BEACH, CALIFORNIA.

CENTERING AND CEMENTING DEVICE.

Application filed June 19, 1922. Serial No. 569,520.

To all whom it may concern:

Be it known that I, JOHN P. BURGHER, a citizen of the United States, and resident of Long Beach, in the county of Los Angeles 5 and State of California, have invented certain new and useful Improvements in Centering and Cementing Devices, of which the following is a specification.

In drilling oil, gas and similar wells it 10 is frequently necessary to pass through strata from which water flows into the well, and it is necessary in some manner to stop this flow of water. This has been frequently done by inserting a stopper of cement, and 15 then drilling through the cement to continue the well to a greater depth.

An object of my invention is to provide a device that will facilitate this operation and enable such cementing to be done accurately 20 and efficiently.

Another object is to provide a device which will insure the cement being properly centered so that it will contact with the walls of the bore on all sides.

25 A further object is to provide a device that will be left in the bore and with the cement will form a reinforced device similar to reinforced concrete.

Other objects will be apparent from the 30 following detailed description and the appended claims.

In the drawings:

Figure 1 is a longitudinal section showing the bore of a well with the device placed 35 in position preparatory to supplying cement thereto.

Figure 2 is a similar view on an enlarged scale showing the cement forced into position.

40 Figure 3 is a perspective view of the packing device.

The bore A of the well is shown as passing through the usual strata B into a stratum C 45 through which water may flow into the well bore. A device D, shown in Figure 3, has two hollow cylindrical end portions 1 and 2 connected by outwardly bowed spring strips 3. The end portions are made somewhat smaller than the bore or casing of the well, 50 and the spring portions 3 should be bowed sufficiently to come in contact with the walls of the bore A. The strips 3 may be fastened to the end portions in any desired manner.

The upper cylindrical end portion 1 is 55 reamed to the desired size, while the lower portion 2 is provided with internal screw

threads 4. A hollow pipe 5 provided with a threaded lower end 6 is employed for placing the device D in position. The device D is screwed upon the lower end of the pipe 5 60 as shown in Figure 2 and lowered to the desired position.

Cement is then forced through the pipe 5 under pressure in any old or desired manner. After the proper amount has been supplied it will be noted by reference to Figure 2 that cement has been forced out of the bottom of the cylindrical portion 2 and forms a plug 7. It has also been forced from the bottom up through the openings between the 65 bowed portions 3 and around the outside of the cylindrical portions 1 and 2 as shown at 8 and 9. The bowed spring portions 3 are imbedded in a hollow cylinder 10 of cement whose internal diameter is that of the end 70 portion 1 and external diameter is that of the bore A of the well.

If the well is to be bored deeper, the plug 7 of cement will be drilled through and the bore extended to the desired depth. In case 75 the desired bottom has been already reached, the device will form a bottom plug obviating the necessity for any further provision for closing the bottom of the bore.

The bowed spring portions not only form 80 with the cement a reinforced cylinder, but when the device D is first placed in position, these portions will center the device and insure a uniform thickness of cement on all 85 sides of the central bore.

The size and proportions of the device D 90 will of course depend upon the circumstances, and the material of which it is made may vary. The exact form of the pipe 5 is immaterial so long as it serves to position 95 the device D and provide a passage for the cement. In general the invention is to be regarded as limited only by scope of the appended claims.

I claim as my invention:

1. A cementing device for wells comprising hollow cylindrical end portions, and outwardly bowed spring metal strips connecting the same.

2. A cementing device for wells comprising hollow cylindrical end portions the lower of which is provided with internal screw threads, outwardly bowed spring metal strips connecting the same, and a positioning device engaging the threaded portion.

3. A cementing device for wells comprising hollow cylindrical end portions of

smaller diameter than the bore of the well, and outwardly bowed spring metal strips contacting with the bore of the well to center the device.

6. 4. A cementing device for wells comprising hollow cylindrical end portions, outwardly bowed spring metal strips connecting the same, and a conduit member which serves to position the device and support cement thereto.

5. A cementing device for wells comprising hollow cylindrical end portions, the lower of which is internally screw threaded, outwardly bowed spring metal strips connecting the same, and a conduit member fitting within the end portions and engaging said screw threaded portion, thus serving as

a means to position the device and supply cement thereto.

6. A plug device for wells comprising 20 hollow cylindrical end portions, outwardly bowed spring metal strips connecting the same, and a cement casing for the whole.

7. A plug device for wells comprising 25 hollow cylindrical end portions, outwardly bowed metal strips connecting the same, and a cement casing forming a plug for the lower end portion, surrounding the end portions, and having the bowed strips embedded therein.

In testimony whereof, I have hereunto subscribed my name

JOHN P. BURGHER.
